Inventor:

Lansing Bonnell

United States Patent Office.

LANSING BONNELL, OF MILWAUKEE, WISCONSIN.

Letters Patent No. 101,422, dated April 5, 1870; antedated March 19, 1870.

HOT-AIR FURNACE.

The Schedule referred to in these Letters Patent and making part of the same

To all whom it may concern:

Be it known that I, LANSING BONNELL, of the city and county of Milwaukee and State of Wisconsin, have invented a new and useful Improvement in Furnaces; and I do hereby declare that the following is a full, clear, and exact description thereof, which will enable those skilled in the art to make and use the same, reference being had to the accompanying drawing forming part of this specification, in which—

Figure 1 is a front view of my invention.

Figure 2, a sectional view in the line *x x*, fig. 1.

Figure 3, a section of the top.

Figure 4, a section in line *y y*, fig. 2.

Similar letters of reference, in each of the figures, indicate corresponding parts.

The object of my invention is the production of a furnace which shall be economical and easily operated.

A is the outside covering to the fire department.

B is the lower part of the furnace and fire-chamber.

C is the inner lower door.

D, slide openings for draught.

E, an upper opening in the door C, through which to shake the grate.

F, outside lower door.

G, opening for draught in door F.

H, upper door through which fuel is fed to the furnace.

I, air-pipes passing up through the furnace, the air passing in at the bottom and up out at the top.

K, a hot-air box above the fire, which can be changed into a magazine for coal by taking out the bottom of it, should it be thought necessary.

L, an air-pipe through which air is taken from the outside and conveyed to the inside of box K, and heated, and passing up round the outside of pipe L.

M, the smoke-pipes.

N, ledges on air-pipes I for hot-air box K to rest on.

O, a wire attached to the draught of door F, so as to regulate the draught without going down cellar.

This furnace is inclosed in a brick casement, and the hot-air is taken out of the top and distributed through the building.

Operation.

Set the furnace wherever wanted, put in any kind of grate, and build a fire in it; regulate your draught by the openings in the doors C and F; build your outside air-conveyer, so as to admit cold air to the bottom of the flues, and to the top pipe L, and a gentle warmth will be diffused, with the use of but little fire. A water-reservoir can be placed on top or round the furnace as may be desired.

What I claim as my invention, and desire to secure by Letters Patent, is—

1. Doors C and F, with their draught-openings, substantially as described.

2. Covering A, air-pipes I, fire-chamber B, and doors C and F with their draught-openings, substantially as described.

3. Covering A, air-chamber K, air-pipes I, and air-conductor L, fire-chamber B, door F, draught-opening G, and wire O, substantially as described.

4. Covering A, fire-chamber B, doors C and F with draught-openings, pipes I, air-chamber K, and air-conductor L, substantially as described.

5. Covering A, fire-chamber B, chamber K with air-pipe L, so arranged that the cold air shall be taken through air-pipe L, and carried down to the bottom of chamber K, and, being heated, rising, and passing out of the top of chamber K, substantially as described.

LANSING BONNELL.
